UNITED STATES PATENT OFFICE.

HANS R. SETZ, OF ST. LOUIS, MISSOURI, ASSIGNOR TO FULTON IRON WORKS, OF ST. LOUIS COUNTY, MISSOURI, A CORPORATION OF MISSOURI.

FUEL-PUMP FOR INTERNAL-COMBUSTION ENGINES.

1,123,815.

Specification of Letters Patent.

Patented Jan. 5, 1915.

Application filed July 11, 1914. Serial No. 850,464.

To all whom it may concern:

Be it known that I, HANS R. SETZ, a citizen of the United States of America, and a resident of the city of St. Louis, State of Missouri, have invented certain new and useful Improvements in Fuel-Pumps for Internal-Combustion Engines, of which the following is a full, clear, and exact description, reference being had to the accompanying drawings, forming a part of this specification.

My invention relates to a pumping device adapted to force liquid fuel to the cylinder or cylinders of an internal combustion engine.

One of the objects is to provide a simple pumping device including a power pump and a manually operable pump, for forcing liquid fuel to the cylinder of an engine when the engine is in operation, and also previous to the engine being placed in operation. The manually operable pump is preferably arranged to draw liquid fuel through the power pump and the latter is preferably provided with a discharge valve, which serves as an inlet valve for the manually operable pump.

Another object of the invention is the production of a manually operable pump having a pump chamber which serves as a manifold or distributing device for the fluid discharged from the power pump.

Figure I is a vertical section of my pumping device. Fig. II is a section taken approximately on the line II-II, Fig. I.

In the accompanying drawings: 1 designates the cylinder of a power pump, and 2 a plunger operable in said cylinder. A cross-head 3, fixed to the outer end of the plunger 2, is adapted to be joined, by a connection rod 4, to a rotating part of an internal combustion engine. The power pump also includes a pump chamber 5 having an inlet port 6 adapted to be opened and closed by an inlet valve 7 and an exhaust port which is opened and closed by an exhaust valve 8. The fuel to be pumped to the engine cylinders is delivered through a supply pipe 9 to a compartment 10 adjoining the pump chamber 5, and during the suction strokes of the pump plunger 2, the inlet valve 7 opens to admit liquid fuel into the pump chamber 5. During the pressure strokes of the pump plunger 2 the liquid

fuel displaced by the plunger is discharged through an exhaust port 11. The liquid fuel passing from the exhaust port 11 flows into a pump chamber 12, and is distributed, through delivery pipes 13, to the different engine cylinders, as will be presently described.

The manually operable pump comprises a plunger 14 passing through a stuffing box 15, and provided with a handle 16 at its outer end. The inner end of the plunger 14, arranged within the pump chamber 12, is provided with a valve member 17 adapted to engage the inner end of a tubular plunger guide 15' extending from the stuffing box 15. When the manually operable pump is not in service, the valve member 17 is seated on the inner end of the tubular member 15 and securely held by a nut 18 screwed onto the pump plunger 14 and engaging the outer face of the stuffing box gland 19. The fluid is thus prevented from escaping into the stuffing box when the power pump is in operation.

The distributing device associated with and forming part of the manually operable pump comprises valve housings 20 communicating with exhaust ports 21 through which the liquid fuel is discharged from the pump chamber 12, the delivery pipes 13 being secured to these valve housings. Each valve housing is preferably provided with a needle valve 22 adapted to be adjusted to partially close the passageway in the valve housing so as to insure a uniform flow of liquid fuel through the different pipes 13, which are not of equal lengths. Before the valve housings 20 are placed in position, exhaust valves preferably in the form of balls 23, are placed in the exhaust ports 21, and the openings through which these balls are inserted may be closed by plugs 24.

The manually operable pump is intended to be used in filling the delivery pipes 13 with liquid fuel before starting the engine, and during the suction strokes of the plunger 14, which is operated by hand, the exhaust valve 8 of the power pump opens to admit the liquid fuel to the pump chamber 12, said exhaust valve 8 serving as an inlet valve for the manually operable pump. During the pressure strokes of the plunger 14 the exhaust valves 23 open to permit the fuel to flow through the different exhaust

ports 21, through the valve housings 20, and into the delivery pipes 13, which lead to the engine cylinders.

I claim:-

- 5 A pumping device comprising a power pump having an exhaust port and an exhaust valve for automatically opening and closing said exhaust port; and a manually operable pump having a pump chamber 10 provided with a plurality of exhaust ports, exhaust valves for opening and closing the last mentioned exhaust ports, the last mentioned exhaust valves being operable independently of the first mentioned exhaust

valve, said pump chamber being in communication with the exhaust port of said power pump, and a manually operable plunger in said pump chamber adapted to draw fluid through the exhaust port of said power pump and into said pump chamber, and 20 adapted to force said fluid through the plurality of exhaust ports in said pump chamber.

H. R. SETZ.
